226,803

BOTTLE

Frank E. Wood, 700 E. 1st St., Tulsa, Okla. 74120

Filed Oct. 20, 1971, Ser. No. 191,142

Term of patent 14 years

Int. Cl. D9—01

U.S. Cl. D9—139

The figure is an elevational view of a bottle showing my new design.

The side opposite that seen is the same in appearance as the side shown and the bottle is circular in all horizontal cross-sections.

I claim:

The ornamental design for a bottle, substantially as shown and described.

References Cited

UNITED STATES PATENTS

D. 3,836	2/1870	Wicks	-----	D9—136
D. 32,426	4/1900	Fenn	-----	D9—136
D. 201,588	7/1965	Linn, Jr.	-----	D9—151

ROBERT C. SPANGLER, Primary Examiner